United States Patent Office.

RICHARD SMITH, OF PHILADELPHIA, PENNSYLVANIA, ASSIGNOR TO
MACKELLAR, SMITHS & JORDAN, OF SAME PLACE.

Design No. 4,008, dated May 3, 1870.

DESIGN FOR TYPE.

The Schedule referred to in these Letters Patent and making part of the same

To all whom it may concern:

Be it known that I, RICHARD SMITH, of the city and county of Philadelphia, Pennsylvania, have originated and produced a new Design for Printing-Type, of which the following is a specification.

The nature of my design is fully represented in the accompanying printed specimens, to which reference is made.

I claim as my invention—

The design for printing-type, as shown.

RICHARD SMITH.
